UNITED STATES PATENT OFFICE.

PAUL ROBITAILLE, OF QUEBEC, QUEBEC, CANADA.

RAILWAY GATE.

Application filed February 18, 1924. Serial No. 693,666.

To all whom it may concern:

Be it known that I, PAUL ROBITAILLE, a subject of the King of Great Britain, residing at Quebec, Province of Quebec, Canada, have invented certain new and useful Improvements in Railway Gates; and I do hereby declare that the following is a full, clear, and exact description of the invention, such as will enable others skilled 10 in the art to which it appertains to make and use the same.

The present invention pertains to a novel railway gate adapted to prevent pedestrians and vehicles from traversing railway crossings during the passage of a train.

The dangers of level crossings are already well known and are recognized by the fact that in many instances they are protected by rails operable by an attendant whose duty 20 it is to lower them by hand when a train approaches and passes the crossing. The principal object of the invention is the provision of a device of this general character, eliminating, however, the necessity of an attendant. In the accomplishment of this object, the guard rails are suitably connected to an electrically operated device which is set in motion by an approaching train. The circuit for operating the device is broken at 30 the track rail and is closed at this point by the railway wheels in passing. At this time the guard rails are lowered and are held in this position by means of an electromagnetic device. When the latter device holds 35 the rails lowered the motor circuit is automatically broken in order to avoid unnecessary flow of current. When the train passes, the magnet is de-energized and the guard rails are raised by means of weights permanently attached to them.

The invention further includes electric lights carried by the guard rails and a sounding device which comes into operation when the rails are lowered.

These devices are preferably connected in parallel with the main circuit and remain in operation until the guard rails begin to turn to their raised position.

The invention is fully disclosed in the following description and in the accompanying drawings in which:

Figure 1 is a perspective view showing the device in use;

Figure 2 is a vertical section through the standard, showing the operating mechanism of the device, the guard rails being lowered;

Figure 3 is a similar detail view, the guard rails being raised;

Figure 4 is a wiring diagram;

Figure 5 is a fragmentary vertical section of the casing, taken at right angles to Figure 2;

Figure 6 is a sectional view of the shaft showing in elevation a portion of the arm carried thereby; and

Figure 7 is a sectional view through the shaft and contact member carried thereby, the latter being in engagement with the switch terminal.

Reference will now be had to these views 70 by means of like characters which are employed to designate corresponding parts throughout.

The body of the device comprises a standard or casing 1 containing the operating 75 mechanism. In the walls of the casing is journaled a shaft 2, the ends thereof being exposed and carrying the guard rails 3. These members are each weighted at one end as at 4, the weights being sufficient to 80 normally hold the rails 3 in raised position, as shown in Figure 3.

A main gear 5 is loosely mounted on the shaft 2, as shown in Figure 5, and has a ratchet 6 formed on one face thereof. On 85 the floor of the casing is mounted a motor 7 operatively connected to the gear 5 by means of a train of gearing 8. To one of the walls of the casing is secured a bracket 9 for supporting an electromagnet 10. An 90 arm 11 is secured to the shaft by means of a pin 12, as shown in Figure 6, and is adapted for attraction by the magnet. Within the casing is also supported a switch terminal 13 adapted for engagement by a contact member 14 carried by the shaft 2. The members 13 and 14 are adapted to control the current in the motor 7, as pointed out more particularly below.

On the top of the casing is supported a post 15 carrying an alarm 16 and a light 17. One of the track rails 18 has fixed thereto an insulated terminal plate 19, as shown in Figures 2 and 4.

The current for operating the device is 105 supplied by a main conductor comprising lines 20 connected to the terminals of a suitable source of power not shown. The electromagnet 10, the rail 18, and the terminal plate 19 are connected in series in the conductor. Each rail 3 carries a plurality of lamps 21, all of which are connected in par-

allel with reference to the conductor 20 on a shunt 21', as shown in Figure 4. The alarm 16 and the lamp 17 on the post are likewise connected in parallel to the conductor 20 on branches 16'. Across the conductor 20 is further connected a shunt wire 22 joined to the motor 7, the switch terminal 13, and the switch contact 14.

In the operation of the device a railway train passing over the rail 18 closes the circuit at the space between the members 18 and 19 by means of the wheels. The magnet 10, alarm 16, and lamps 17 and 21 are now set into operation, as is apparent from the wiring diagram. Since in neutral position the guard rails 3 are raised, the contact 14 is in engagement with the terminal 13, as shown in Figure 3. Consequently the motor 7 is set in motion, causing rotation of the large gear 5. A pawl 23 is pivotally carried by the arm 11 and is held in engagement with the ratchet by means of a guide 24 when the rails 3 are raised. The ratchet 6 obviously moves with the gear 5, carrying with it the arm 11 until the latter is attracted by the magnet 10. When the arm engages the magnet the contact 14 is separated from the terminal 13, whereby the motor circuit is broken, as illustrated in Figures 2 and 4. In this position the pawl 23 is disengaged from the ratchet because of its engagement with the bracket 9. The motor is now stopped, but the rails are held down because of the engagement between the arm 11 and the magnet 10. The magnet remains energized while the car wheels are passing over the rail 18, and during this period the rails 3 are held in lowered position. When the train has passed the plate 19 the series circuit is broken and the magnet becomes dead. At the same time the members

16, 17 and 21 cease to operate. The weights 4 now raise the rails 3, and the parts are returned to the position shown in Figure 3. It will be apparent that the action of the weights thus brings the pawl 23 again into engagement with the ratchet 6.

While a specific embodiment of the invention has been illustrated and described, it is to be understood that various alterations in the details of construction may be made without departing from the spirit of the invention as indicated by the appended claim.

Having thus fully described the invention, what I claim as new and desire to protect by Letters Patent is:—

A railway gate comprising a standard, a shaft journaled therein, weighted rails secured to said shaft, a bracket disposed within the standard, an electric motor supported on said bracket, a gear loosely mounted on the shaft, a ratchet carried by said gear, an operative connection between said gear and the motor, a switch terminal connected to said motor, a switch contact carried by the shaft and adapted to engage said terminal, means for supplying current to said motor, an electromagnet connected in series with said means, an arm secured to the shaft and adapted for attraction by the magnet, a pawl pivotally carried by said arm and adapted for engagement with the ratchet and for contact with said bracket to be released from the ratchet, and a guide secured within the standard for bringing the pawl into engagement with the ratchet upon rotation of the shaft due to the weighted rails secured thereto.

In witness whereof I have hereunto set my hand.

PAUL ROBITAILLE.
